The Westinghouse Air Brake Company, Wil-
merding, Pa., a corporation of Pennsylvania

Application July 30, 1932, Serial No. 626,501

14 Claims. (Cl. 230—212)

This invention relates to fluid compressors and particularly to fluid compressors of the reciprocating piston type.

An object of the invention is to provide a fluid compressor of the reciprocating piston type wherein a single piston is utilized to compress fluid in two stages during each cycle of operation or during a single revolution of the crank shaft driving the piston.

10 A further object of the invention is to provide a compact two stage compressor which requires practically no more space or parts than is required for a single stage compressor.

15 A further object of the invention is to provide a fluid compressor having the above noted characteristics wherein provision is made for pre-cooling the fluid entering the compressor and for adequately cooling the compressed fluid during the progress of compression, thereby increasing 20 the efficiency of the apparatus.

25 These and other objects of the invention that will be made apparent throughout the further description thereof are attained by means of the fluid compressor hereinafter described and illustrated in the accompanying drawing; wherein,

Fig. 1 is a vertical sectional view of a fluid compressor embodying features of the invention; and

30 Fig. 2 is a transverse sectional view of the apparatus shown in Fig. 1, taken on the line 2—2 thereof.

35 Referring to the drawing, the compressor comprises a crank case section 3, a guide cylinder section 4 mounted thereon, a compressor cylinder section 5 mounted upon the guide cylinder section, a head section 6 mounted on the compression cylinder section and an intake section 7 secured to the head section.

40 The crank case section 3 comprises a casing 11, part of which is shown, and which contains a crank chamber 12. The casing also comprises an annular chamber 13 for containing a cooling fluid such as water which is supplied to the chamber in a manner to be hereinafter described. The chamber 13 surrounds a circular opening 14 in the crank case through which the piston rod 15 projects and into which the lower end of a guide cylinder 16 extends, the guide cylinder constituting an integral part of the casing 17 of the guide cylinder section 4, which is secured to the upper attaching face 18 of the casing 11.

45 The guide cylinder casing 17 is provided with a valve chamber 19 containing an outlet check valve device 21 of the disc type, which comprises a seat disc 22 that is inserted in an opening 23 in

the casing 17 and which is retained in assembled position by a retaining cage 24, threaded in an opening 25 in the casing 17 and which is aligned with an opening 20 in the outer wall of the casing 17 through which the cage may be inserted. The opening 20 is closed by a plate 26 that may be secured to the casing 17 by means of screws, not shown.

5 The seat disc 22 is provided with a series of ports 27 disposed in a circle and which are adapted to be closed by a valve disc 28 that is yieldingly held in seated position by means of a spring 29 that is disposed between the valve disc 28 and the flange 31 of a retaining washer 32 that is attached to the seat disc 22 by means of a bolt 33. 10

15 The valve chamber 19 communicates with a discharge or outlet passage 34 that is adapted to be connected to a reservoir, not shown, for receiving the compressed fluid. The ports 27 in the seat disc 22 establish communication between 20 the valve chamber 19 and a passage 35, the purpose of which will hereinafter appear.

25 The compression cylinder section 5 comprises a casing 36 containing a cylindrical bore 37 that is of greater diameter than the diameter of the guide cylinder 16 and is adapted to receive an enlarged head 38 of a piston 39 having a reduced cylindrical portion engaging the guide wall of the guide cylinder 16, and which is pivotally connected to the piston rod 15 by means of a wrist pin 40. 30

35 The head section 6 comprises a casing 41 which serves to close the end of the cylindrical bore 37 and which is provided with a valve chamber 30 containing an inlet disc valve device 42, which comprises a seat disc 43 mounted within an opening 44 in the casing 41 and which is retained in operative position by means of a cage 45 that is threaded into an opening 46 in the outer wall of the casing 41. The seat disc 43 is provided 40 with a series of ports 47 that are adapted to be closed by means of a valve disc 48 that is yieldingly held in engagement with the seat disc 43 by means of a spring 49 that is disposed between the valve disc 48 and the flange 51 of a retaining washer 52, that is secured to the seat disc 43 by means of a bolt 53. The valve chamber 30 communicates with an inlet passage 54, communicating with the inlet passage 55 in the inlet section 7. The passage 55 may be connected to a conduit, not shown, through which air at atmospheric pressure is supplied to the compressor. The ports 47 establish communication between the valve chamber 30 and the bore 37 of the compression cylinder section 5. 45

The enlarged head 38 of the piston 39 serves to divide the bore 37 into a compression chamber 56 on the upper side of the piston head and an annular compression chamber 57 on the under side of the piston head 38, the maximum volumetric capacity of which is considerably smaller than the maximum volumetric capacity of the compression chamber 56. The volumetric capacity of the chamber 57 is maximum when the piston 39 is in its uppermost position and the volumetric capacity of the chamber 56 is maximum when the piston 39 is in its lowermost position as shown in Fig. 1.

The passage 35 opens into the annular compression chamber 57 as indicated in Fig. 1, and the head 38 of the piston is provided with a ring type check valve device 58 which comprises a split piston ring 59 that is disposed within an annular groove 61 in the enlarged head 38 of the piston, the groove being of greater width than the thickness of the ring 59, so that the ring is free to move respectively into engagement with sealing faces 62 and 63 of the groove 61 as the piston is moved downwardly and upwardly. A series of perforations 64 establish communication between the groove 61 and the compression chamber 57 at the lower side of the piston head 38.

The operating cycle of a two stage compression operation of the compressor is as follows. Assuming the piston 39 to be in the uppermost position, the initial downward movement of the piston moves the sealing seat 62 of the groove 61 into sealing engagement with the valve ring 59. Further downward movement of the piston creates suction within the chamber 56 and causes air at atmospheric pressure to be drawn into the compression chamber 56 on the upper side of the piston. During the downward movement of the piston, the compressed fluid within the annular compression chamber 57 at the under side of the piston head 38, which has been previously forced into the chamber 57 in a manner to be herein-after described, is compressed within the chamber 57 until the pressure therein overcomes the tension of the spring 29 of the discharge check valve device 21 and the pressure within the valve chamber 19 and forces the valve disc 28 to open position. With the valve disc 28 open, fluid under pressure within the compression chamber 57 flows into the valve chamber 19 and thence to the reservoir, not shown, through the passage 34.

Upon completion of the downward stroke of the piston 39, the spring 49 of the intake check valve device 42 forces the valve disc 48 into closed position and prevents a reflux of the fluid drawn into the chamber 56 through the ports 47 of the check valve device 42. Upon the upward stroke of the piston 39, the sealing seat 62 of the piston groove 61 is moved away from the valve ring 59 which is frictionally retained at rest against the cylinder wall during the initial movement of the piston, thereby opening communication from the compression chamber 56 to the compression chamber 57 through the ports 64 in the piston head 38. Accordingly, as the piston is moved upward the fluid within the compression chamber 56 is forced into the relatively smaller compression chamber 57 through the ports 64, thereby increasing the pressure of the fluid within the chamber 57 in accordance with the difference in maximum volumetric capacity of the two chambers, it being understood that the maximum volumetric capacity of the chamber 57 is considerably less than the maximum volumetric capacity of the chamber 56.

As before stated, upon the down stroke of the piston, when the pressure of the fluid within the chamber 57 exceeds that of the pressure within the valve chamber 19 and the reservoir associated therewith sufficiently to overcome the tension of the spring 29, the compressed fluid is forced into the valve chamber 19 and into the reservoir, not shown. Upon termination of the down stroke, the valve disc 28 is closed by the spring 29 and upon the succeeding up stroke of the piston, the fluid drawn into the chamber 56 during the down stroke of the piston will be forced into the annular compression chamber 57 and the compression operation is then repeated in the manner above described.

It will be apparent from the foregoing that a compressor having a single piston is so constructed that fluid is compressed in two stages by the single piston during a single cycle of operation of the piston and consequently the compressor may be of relatively compact construction.

The efficiency of the compressor is further enhanced by reason of an improved means for extracting the heat from the compressed fluid during the compression operation, which means comprises a system of conduits and chambers through which cooling fluid such as water is advantageously circulated for obtaining maximum cooling results. The conduit system for the cooling fluid includes passages 65 and 66 within the casing 17 of the cylinder section 4, which register respectively with passages 67 and 68 leading from the chamber 13 disposed within the upper wall 69 of the casing 11 of the crank case section 3. The casing 17 is also provided with two arcuate chambers 71 on opposite sides of the guide cylinder 16 and which communicate with the chamber 13 through openings 72 which extend through the flange 73 of the casing 17 and are aligned with openings 74 in the wall of the casing 11 as indicated in Figs. 1 and 2.

The compression cylinder casing 36 of the compression cylinder section 5 is provided with a chamber 75 that extends partially around the bore 37 and which communicates with the chambers 71 in the casing 17 through aligned passages 76 in the lower wall of the chamber 75 and the upper wall of the chambers 71. The casing 36 is also provided with a passage 77 which registers with the passage 65 in the casing 17.

The head casing 41 of the head section 6 is provided with an annular chamber 78 that is disposed over the end of the chamber 56 as indicated in Fig. 1 and communicates with the chamber 75 through passages 79 in the inner wall of the casing 41 and the upper wall of the chamber 75. The head casing 41 is also provided with a passage 81 which registers with the passage 77 in the casing 36 and with a passage 82 opening into a chamber 83 in the casing 60 of the inlet section 1 which surrounds a portion of the passage 55 as indicated in Fig. 1.

The passage 66 in the casing 17 opens into a chamber 84 which surrounds the valve chamber 19. The chamber 84 opens into an outlet passage 85 in the casing 17 through a passage 86 and the passages 85 registers with an outlet passage 87 leading from the chamber 78 in the said casing 41. The passage 85 is connected to a pipe 88 of a water circulating system, not shown.

Cold water is supplied to the cooling conduit and chambers of the compressor through a pipe 89 and first enters the chamber 83 surrounding the inlet passage 55, thus serving to precool the air entering the compressor through the passage 75.

55. The cooling fluid then flows through passage 81 to the passages 77 and 65 in the casings 37 and 17 respectively, and thence into the annular chamber 13 in the casing 11, where the cooling 5 fluid serves to cool a portion of the crank case and maintain the lubricant in the crank case at a proper operating temperature.

10 Cooling fluid flows from the chamber 13 into the chambers 71 through the openings 12 and thence flows through openings 76 into the chamber 75 surrounding the cylinder bore 37 of the casing 36. Fluid compressed by the piston in the compression chambers 56 and 57 is thus cooled during the act of compression by reason of the 15 cooling fluid within the chamber 75 and the passage 77. Cooling fluid flows from the chamber 75 to the chamber 78 in the head casing 41 through the passages 79 and thence flows to the pipe 88 through the passages 87 and 85.

20 Cooling fluid also flows from the chamber 13 through passages 69 and 66, chamber 84 and passage 86 to the outlet passage 85 that is connected to the discharge pipe 88, thus cooling the valve chamber 19 and the air leaving the compressor 25 through the passage 34. Any means may be provided for cooling the water leaving the compressor through the pipe 88 before it is again returned to the compressor through the pipe 89, or the compressor may be supplied with cooling fluid from a 30 water supply system, not shown, in which case the cooling fluid passing through the pipe 88 is discharged to a drain.

35 From the foregoing it is apparent that a compact and highly efficient compressor is provided wherein the fluid is compressed in two stages by a single piston and wherein the air is pre-cooled before entering the compression chamber of the compressor and cooled during the compression 40 operation. Since the walls of the piston guide cylinder are cooled, the temperature of the piston is maintained relatively low and tends to further cool the fluid both in the first and second stages of compression. Since the temperature of the 45 crank case chamber 12 is maintained relatively low due to the large body of cooling fluid circulated through the chamber 13 in the upper part of the casing 11, the interior of the piston is not subjected to relatively hot gases as would be the case where no provision is made for cooling the 50 lubricant within the crank case chamber.

55 While but one embodiment of the invention is disclosed herein and showing a single piston two stage compressor, it is obvious that a multiple piston compressor having more stages of compression may be embodied in a single compressor unit and that many changes, additions and omissions may be made to the compressor construction disclosed without departing from the spirit of the 60 invention.

65 Having now described my invention, what I claim as new and desire to secure by Letters Patent, is:

1. The combination with a compressor having a chamber, a movable abutment dividing said chamber into compression chambers on opposite sides respectively of said abutment having unequal maximum volumetric capacities and connected by a communication between the chamber wall and the abutment through which fluid compressed by said abutment moving to reduce the volumetric capacity of the compression chamber having the larger maximum volumetric capacity is forced to the chamber having the lesser maximum volumetric capacity, of a ring type 70 check valve cooperating with said abutment and

said chamber wall for controlling said communication and for preventing a reflux of the fluid flowing through said communication.

2. The combination with a compressor having a chamber, a movable abutment dividing said chamber into compression chambers on opposite sides respectively of said abutment having unequal maximum volumetric capacities and connected by a communication through which fluid compressed by said abutment moving in one direction to reduce the volumetric capacity of the compression chamber having the larger maximum volumetric capacity is forced to the chamber having the lesser maximum volumetric capacity, of a valve means cooperating with a wall of said chamber and said abutment for controlling said communication operative upon movement of said piston in the opposite direction for preventing a reflux of the fluid flowing through said communication, an intake check valve for controlling the ingress of fluid to said compression chamber having the larger maximum volumetric capacity and an outlet check valve for controlling the egress of fluid from said compression chamber having the lesser maximum volumetric capacity. 20

25 3. The combination with a compressor having a chamber, a movable abutment dividing said chamber into compression chambers on opposite sides respectively of said abutment having unequal maximum volumetric capacities, which capacities are varied upon movement of the abutment in one direction so that as the capacity of one compression chamber is reduced, the capacity of the other compression chamber is increased, said compression chambers being connected by a communication through which fluid compressed by said abutment moving to reduce the volumetric capacity of the compression chamber having the larger maximum volumetric capacity is forced into the chamber having the lesser maximum volumetric capacity, of a valve means cooperating with a wall of said chamber and said abutment for controlling said communication operative upon movement of said piston in the opposite direction for preventing a reflux of the fluid flowing through said communication. 30

35 4. The combination with a compressor having a chamber, a movable abutment dividing said chamber into compression chambers on opposite sides respectively of said abutment having unequal maximum volumetric capacities, which capacities are varied upon movement of the abutment in one direction so that as the capacity of one compression chamber is reduced, the capacity of the other compression chamber is increased, said compression chambers being connected by a communication through which fluid compressed by said abutment moving to reduce the volumetric capacity of the compression chamber having the larger maximum volumetric capacity is forced into the chamber having the lesser maximum volumetric capacity, of a valve means cooperating with a wall of said chamber and said abutment for controlling said communication operative upon movement of said piston in the opposite direction for preventing a reflux of the fluid flowing through said communication, an intake check valve for controlling the ingress of fluid to said compression chamber having the larger maximum volumetric capacity and an outlet check valve for controlling the egress of fluid from said compression chamber having the lesser maximum volumetric capacity. 40

45 5. The combination with a compressor having a piston cylinder, a piston working within said

cylinder and dividing it into chambers on opposite sides respectively of said piston, having unequal maximum volumetric capacity and connected by a communication through which fluid 5 compressed by said piston moving in one direction in the chamber having the larger maximum volumetric capacity is forced to the chamber having the lesser maximum volumetric capacity, of a valve means cooperating with a wall of said cylinder and said piston for controlling said communication and operative upon movement of said piston in the opposite direction for preventing a reflux of the fluid flowing through said communication.

6. The combination with a compressor having 15 a piston cylinder, a piston working within said cylinder and dividing it into chambers on opposite sides respectively of said piston, having unequal maximum volumetric capacity and connected by a communication between the cylinder 20 wall of said cylinder and said piston through which fluid compressed by said piston moving in one direction in the chamber having the larger maximum volumetric capacity is forced to the chamber having the lesser maximum volumetric capacity, of a valve means cooperating with a wall of said cylinder and said piston for controlling said communication and operative upon movement of said piston in the opposite direction for preventing a reflux of the fluid flowing through 25 said communication.

7. The combination with a compressor having a piston cylinder, a piston working within said cylinder and dividing it into chambers on opposite sides respectively of said piston, having unequal maximum volumetric capacity and connected by a communication between the cylinder 30 wall and the piston, the chamber having the larger maximum volumetric capacity having an inlet passage and the other chamber having an outlet passage, of an intake valve for controlling the flow of fluid through the inlet passage and preventing the flow of fluid from the associated chamber through said passage, an outlet valve for controlling the flow of fluid through the outlet passage and permitting the flow of fluid therethrough from its associated chamber, and a ring type check 35 valve cooperating with said cylinder wall and said piston for permitting the flow of fluid through said communication between said chambers only from the chamber having the inlet passage to the chamber having the outlet passage.

8. The combination with a compressor having a piston cylinder, a piston working within said cylinder and dividing it into a first stage compression chamber on one side of said piston and having an inlet port and a second stage compression chamber on the other side of said piston and having an outlet port, of an inlet check valve controlling the inlet port, an outlet check valve controlling the outlet port, the said piston having a passage through which fluid in the first stage compression chamber may flow to the second stage compression chamber, and a ring type check valve for controlling said passage in the piston for permitting fluid under pressure to flow from the first stage compression chamber to the second stage compression chamber and operative upon movement of the piston in one direction for preventing fluid under pressure from flowing from the second stage compression chamber to the first stage compression chamber.

9. A fluid compressor comprising a casing having a crank chamber, a guide cylinder, a compression cylinder and a cylinder head, and a 75 jacket covering walls of each of said elements and

divided into separate chambers, one adjacent each element and connected for providing a conduit through which cooling fluid may be forced for progressively contacting with the casing for said elements in the order defined.

10. A fluid compressor comprising a casing having a fluid intake passage, a compression cylinder, a guide cylinder, a crank chamber and an outlet passage, and a jacket covering walls of each of said elements and passages and divided into separate chambers, one adjacent each element and connected for providing a conduit through which cooling fluid may be forced for progressively contacting with the casing for said elements and passages in the order defined.

11. A fluid compressor comprising a sectional casing having a crank chamber, a guide cylinder, a compression cylinder and a cylinder head, each of said elements having an integral jacket for providing a conduit, the said sections being connected together to constitute a compressor casing and with their respective conduits in registry whereby a continuous conduit is formed through which cooling fluid may be forced for progressively contacting with the casing sections of said elements.

12. A compressor comprising a sectional casing having a compression chamber section, a head section cooperating with one end of said chamber section, a crank case section, and a compressor piston guide section interposed in cooperating relation between the opposite end of said chamber section and said crank case section, the walls of said casing sections having passageways therein respectively cooperating to direct the flow of cooling fluid in succession through said chamber section, said guide section, said crank case section, said guide section, said chamber section, and said head section.

13. A compressor comprising a sectional casing having a compression chamber section, a head section cooperating with one end of said chamber section, an intake passage section cooperating with said head section, a crank case section, and a compressor piston guide section interposed in cooperating relation between the opposite end of said chamber section and said crank case section, the walls of said casing sections having passageways therein respectively cooperating to direct the flow of cooling fluid in succession through said intake section, said head section, said chamber section, said guide section, said crank case section, said guide section, said chamber section, and said head section.

14. A compressor comprising a sectional casing having a section containing a compression chamber adapted to have a compressor piston operate therein, a head section cooperating with one end of the chamber section for closing the compression chamber and having an intake valve mechanism therein, a crank case section, and a section for guiding the compressor piston, said guiding section being interposed in cooperating relation between the opposite end of said chamber section and said crank case section and having a discharge valve mechanism therein, said casing sections having passageways therein respectively cooperating to direct the flow of cooling fluid in succession through said chamber section, said guiding section, said crank case section, said guiding section and said head section past said intake valve mechanism, and also to direct the flow of cooling fluid from said crank case section through said guide section past the said discharge valve mechanism.
